UNITED STATES PATENT OFFICE.

FREDERICK H. AULD, OF COLUMBUS, OHIO, ASSIGNOR TO THE D. L. AULD COMPANY, OF COLUMBUS, OHIO.

HUB-CAP-ATTACHING MEANS.

Application filed September 8, 1924. Serial No. 736,494.

To all whom it may concern:

Be it known that I, FREDERICK H. AULD, a citizen of the United States, residing at Columbus, in the county of Franklin and State of Ohio, have invented new and useful Improvements in Hub-Cap-Attaching Means, of which the following is a specification.

The present invention is directed more particularly to improvements in hub cap attaching means for automobile wheels, but is not necessarily limited to such use.

The primary object of the invention is to provide a device of this character so constructed that the cap can be easily and positively locked upon the hub of an automobile wheel without the use of threads and in such manner as to positively prevent leakage of grease and the entrance of dust and grit. It is a well-known fact that hub caps now used are formed from comparatively thin metal which necessitates the use of fine threads, which being the case the threads soon become stripped resulting in disengagement of the cap and leakage of grease and it is to overcome these defects that the present invention has been perfected.

A still further object of the invention is to provide a device of this character wherein the parts for attaching the cap to the hub are reduced to a minimum, but are so correlated as to permit the cap to be easily and quickly removed from the hub and when replaced held positively against accidental disengagement.

With these and other objects in view, this invention resides in the novel features of construction, formation, combination and arrangement of parts to be hereinafter more fully described, claimed and illustrated in the accompanying drawing, in which:

Figure 1 is a longitudinal sectional view.

Figure 2 is a sectional view on line 2-2 of Figure 1.

Figure 3 is a sectional view on line 3-3 of Figure 1.

Figure 4 is a sectional view on line 4-4 of Figure 1.

Figure 5 is a detail sectional view through the cap and shell.

Referring to the drawings 1 designates the hub flange having the collar 2 in which the end of the axle (not shown) extends. The collar is provided with a pair of arcuate ribs 3, the ends of which are spaced a sufficient distance to provide passages 4, the ends

of said ribs constituting stops 5, the purpose of which will later appear.

The hub cap 6 may be of any suitable design and includes a dome 7 provided with wrench engaging faces. The rim of this cap differs from the customary cap in the provision of the diametrically disposed arcuate flanges 8, which are of such length as to pass freely through the passages 4 when applying or removing the cap.

The dome 7 has suitably fixed interiorly thereof a disk 9, said disk being provided with a pair of diametrically opposed segments 10, the faces of which are beveled in opposite directions. These segments are provided with recesses 11, the purpose of which will appear later.

Mounted within the cap 6 is a steel shell 12 which includes a crown 13 adapted to extend a spaced distance into the dome 7, said shell including an annular seat 13' adapted to tightly engage the rim of the collar 2 when the cap is in its operative position.

The outer edge of the shell terminates in a rim 14 and is provided with diametrically opposed longitudinally curved wings 15, the ends of which being adapted to contact with the stops 5 when said wings occupy the passages 4 and when the cap is in place, said stops serving to prevent rotation of the shell. It will be observed that the shell is of substantially the same general contour as the cap 6 so as to fit neatly therein.

A disk 16 is suitably secured to the upper surface of the crown 13 of the shell and like the disk 9 is provided with a pair of oppositely beveled segments 17 adapted to slidably engage the segments 10 of the disk 9. The segments 17 are provided with lugs 18 adapted to snap into engagement with said recesses of the segments 10 when the cap 6 has been rotated to its final or operative position, thereby preventing accidental disengagement of the cap.

In operation the cap 6 is placed relative to the collar 2 to permit the flanges 8 to pass through the passages 4 until they rest upon the annular shoulder 19 carried by the collar and aline with the grooves 20 formed between the shoulder and ribs 3, and at which time the wings 15 occupy the passages with their ends engaged with the stops 5. Upon rotating the cap in a clockwise direction the flanges 8 will enter the

grooves 20, but owing to the fact that the wings 15 are interlocked with the stops 5 the shell is held against rotation. Continued rotation of the cap will cause the 5 beveled faces of the segments 10 to ride upon the similar faces of the segments 17, thereby causing the flanges 8 to tightly engage the ribs 3, whereupon the shell 12 is subjected to pressure and forced downward- 10 ly until the seat 13' tightly engages the rim of the collar 2 to provide a liquid and dust tight metal to metal connection, thereby eliminating the use of gaskets or the like. Further rotation of the cap will cause the 15 lugs 18 to snap into engagement with the recesses 11, thereby preventing accidental rotation of the cap in a reverse direction. Owing to the inherent resiliency of the shell 12, the beveled faces of the segments 20 10 and 17, when fully engaged will hold the seat 13' tightly, and to some extent yieldably engaged with the rim of the collar 2. It will be of course understood that a suitable wrench will be used in connection 25 with the dome 7 to remove or replace the cap.

To limit the rotation of the cap in either direction a pin 21 is placed in one end of one of the grooves 20 and with which one 30 of the flanges 8 contacts.

From the foregoing description it will be seen that a structure is provided which is more particularly designed for use in connection with hub caps, but can be used with 35 equal success in connection with radiator caps, gasoline tanks and in fact any place wherein it is desired to obtain a liquid and dust tight joint without the use of threads.

What is claimed is:

40 1. The combination with a hub collar, of a cap, a shell mounted in the cap, means for interlocking the shell with the collar to prevent rotation thereof during rotation of the cap, the same means serving to interlock the

cap with the collar, and means for imparting endwise movement to the cap and shell when the cap is rotated, thereby causing the shell to seat upon the collar and the cap to bindingly engage the cap interlocking means. 45

2. The combination with a hub collar, of 50 a pair of ribs carried by the collar and having spaced ends constituting stops, a cap having flanges for co-operative engagement with the ribs, a shell mounted in the cap and provided with wings for interlocking 55 engagement with the stops to prevent rotation of the shell during rotation of the cap, and means for exerting endwise movement of the cap and shell in opposite directions to cause the flanges to tightly engage the 60 ribs and the shell to seat upon the rim of the hub collar.

3. The combination with a hub collar, of 65 a cap for interlocking engagement with the collar, a relatively resilient shell mounted in the cap, means for interlocking the shell with the collar to prevent rotation thereof during rotation of the cap, and means operable upon rotation of the cap to move the cap and shell endwise to flex the latter for 70 yieldable engagement with the rim of the collar.

4. The combination with a hub collar, of 75 a cap having oppositely beveled segments mounted therein, a shell mounted in the cap and having beveled segments for co-operation with the first named segments, means for interlocking the shell with the collar to prevent rotation thereof when the cap is rotated, said segments serving to move the 80 cap and shell endwise in opposite directions to cause the shell to tightly engage the rim of the collar and the cap to interlock with said collar.

In testimony whereof I have hereunto set 85 my hand.

FREDERICK H. AULD.
